INVENTOR.

Charles H. Allen
BY
Horatio E. Bellow
ATTORNEY

UNITED STATES PATENT OFFICE.

CHARLES H. ALLEN, OF ATTLEBORO, MASSACHUSETTS.

FASTENER.

Application filed May 5, 1922. Serial No. 553,729.

To all whom it may concern:

Be it known that I, CHARLES H. ALLEN, a citizen of the United States, residing at Attleboro, in the county of Bristol and State of Massachusetts, have invented certain new and useful Improvements in Fasteners, of which the following is a specification.

My invention relates to fasteners of the latch type adapted for use upon wrist bands and the like.

The essential objects of my invention are security, inexpensiveness of construction, compactness, and the avoidance of objectionable projections.

To the above ends essentially my invention consists in such parts and in such combinations of parts as fall within the scope of the appended claim.

In the accompanying drawings which form a part of this specification,

Figures 1 and 2 are a side elevation and a plan view respectively of my fastener showing portions of the adjacent ends of a wrist ribbon or band.

Figure 3, a section of the fastener on line 3—3 of Figure 1.

Figures 4 and 5, section of the same on line 4—4 of Figure 2 showing the parts in closed and open positions respectively, and

Figure 6, a bottom plan view of the same.

Like reference characters indicate like parts throughout the views.

In detail the fastener comprises a substantially flat plate or body 10 with its forward portion 11 transversely offset downwardly, as at 12, so that the portions 10 and 11 lie in parallel planes. The central portion of the offset is cut away as at 13, and

extends into the portion 10 as at 14, the whole forming an elongated slot or opening

15. Integral with the portion 11 of the plate 10 is a guard hook 17 extending upwardly and rearwardly whose beak portion 18 is parallel with the portion 11. Midway its length the plate or body has lateral extensions 20 whose ends are upwardly folded to form flat pliable clamping fingers 21 to frictionally embrace and retain one end of a wrist ribbon 23 against the lower face of the body. Inwardly and downwardly bent lateral lugs 25 at the rear end of the body serve as guides for a slidable plate 27 which

extends through the slot 15. The rear portion of the plate 27 rests against the lower face of the plate 10, while its forward portion rests upon the upper face of the body portion 11. It will be observed that the slot 15 in the offset serves as a guide for the forward portion of the slide 27. Integral with the forward end of the slide is an operating hook 29 loosely embraced by the hook 17 and whose beak 30 is shorter than the beak 18. Cut and raised from the material of an intermediate portion of the slide is an upwardly inclined finger 32 whose free end is 65 spaced from the beak 30 and in the plane of the beak 18. Upon the rear end of the slide is an upturned ear or finger piece 34 for manually withdrawing the slide.

In this instance a ring or loop 36 is shown attached to the end of the ribbon 23 opposite the fastener, but it will be understood that the loop may be that of a wrist watch.

In operation the slide is initially drawn rearwardly to open position as shown in Figure 5 wherein the finger 32 is spaced from the beak 18, and the end of the beak 30 registers with the end of the beak 18. The loop 36 is inserted into the resultant opening and brought into the cavity of the hook 29 and drawn forwardly whereby the finger 32 is advanced into contact with the hook 17, thus closing the temporary space or opening.

It will be noted that the fastener may be cut and bent from sheet metal and that the guiding means of the slide affords compactness of structure and avoids projecting parts.

I claim:—

In a fastener of the type set forth, a body plate including an intermediate offset portion provided with a guide slot, a guard hook upon the forward end of the plate, guides upon the rear end of the body plate, a slide upon the plate in the guides and extending through the slot, an operating hook upon one end of the slide within the first hook, and a finger on the slide adapted to abut against the first hook.

In testimony whereof I have affixed my signature.

CHARLES H. ALLEN.
